UNITED STATES PATENT OFFICE.

LOUIS V. ARONSON, OF NEWARK, NEW JERSEY.

DESIGN FOR AN IGNITER.

45,407.

Specification for Design.

Patented Mar. 17, 1914.

Application filed January 16, 1914. Serial No. 812,607. Term of patent 7 years.

To all whom it may concern:

Be it known that I, LOUIS V. ARONSON, a citizen of the United States, residing in the city of Newark, in the county of Essex and State of New Jersey, have invented a new, original, and ornamental Design for Igniters, of which the following is a specification, reference being had to the accompanying drawings, forming part thereof.

Figure 1 represents a side elevation illustrating my new design; and Fig. 2 represents a rear elevation of the same.

As shown in the drawing, the leading or

material feature of my design consists in an ornamental figure of a dog in a sitting position, having mounted on its back a spark-producing alloy, and extending out of its head, the handle of a striker.

I claim:

The ornamental design for an igniter as shown and described.

LOUIS V. ARONSON.
